TURRET TOP LUGGAGE COMPARTMENT

William E. Martin, Kewanee, Ill.

Application March 27, 1947, Serial No. 737,476

11 Claims. (Cl. 224—42.1)

1

This invention is directed to a newly constructed turret top luggage compartment adapted specifically for use and attachment upon the top of the passenger body portion of a conventional automobile.

It is one of the main objects of this luggage compartment to provide a rigidly constructed base adapted to be positioned upon the top of the car body in such a manner as to receive adequate support about the peripheral margins of the auto top, which actually present the strongest portion of the top due to its relatively abrupt curvatures at the peripheral portions thereof. This base is provided with a baggage supporting floor that is adapted to bridge the top of the automobile so that the weight of the baggage will not be supported by any of the flatter and greater radii portions of the automobile top.

It is a further object of the present invention to provide a base of the kind above noted, which is provided with a continuous supporting skirt connected for positioning the floor of the luggage compartment in a general, normal, horizontal plane, the skirt also being so shaped at its terminal edge portions as to conform substantially with the peripheral contour of the contacting portion of the auto top that is engaged by the skirt. It is another advantage of the present invention to provide the skirt portion of the base with a suitable resilient footing which extends entirely about the terminal edges of the skirt and which may in gasket fashion seat firmly upon the upper supporting portion of the automobile top, thereby producing a finished joint which is adapted to blend the supported luggage base into the contour of the top of the automobile structure.

Another object of the present invention is to provide a hinged cover suitably connected with the base and cooperating with the peripheral portion of the floor of such base to form a dust tight and rainproof enclosure for the protection of baggage carried within the luggage compartment.

This invention also contemplates the further concept of constructing the turret top with a preformed shape adapted to provide a fixed base integral with the car top and which may be used for transporting boats, ladders, or other units. Or such base may be used to carry baggage and the like protected by an attached cover.

It is a further object of the present design of luggage compartment to shape the cover and base in complementary fashion to form a beautifully streamlined luggage compartment, which in its entirety blends into the outline of the car body, as accentuated by the particular design of the base, which in its attachment blends sub-

2

stantially into the rounded and curved portion of the top of the car body.

It is another object of the present invention to provide a suitable hinge connecting the cover with the base of the luggage compartment, which for all normal purposes permits the cover to swing upwardly to provide access to the luggage compartment, such hinge also being constructed for quick disassembly, permitting removal of the cover when this is desired. By removing the cover, the remaining base portion can be used for supporting larger objects upon the car top with the introduction and use of proper fastening means such as straps and the like. In this manner a boat, oversized camping equipment, ladders or any other transportable units may be carried upon the car top through the instrumentality of the large and rigid supporting floor of the base, receiving its support by the long peripheral skirt and the attached footing which engages the peripheral portions of the automobile top, thereby distributing the supported weight of the luggage compartment and contents over a large portion of the car top.

The base is attached to the top through suitable fixtures that are detachable with respect to the car top or to the base, so that the entire base can be removed from the car top and stored together with the cover until needed. When this base is in use it will serve to protect the car top from injury or damage particularly in an accident that would result in an overturning of the car or a roll over.

All other objects and advantages relating to the turret top luggage compartment of the present invention shall hereinafter appear in the following detailed description having reference to the accompanying drawings forming a part of this specification.

In the drawings:

Fig. 1 is a general diagrammatic side elevational view of a conventional automobile incorporating the turret top luggage carrier of the present invention;

Fig. 2 is an enlarged side elevational view of the luggage compartment illustrating certain details of construction thereof;

Fig. 3 is a front elevational view of the luggage compartment as applied to the top of an automobile;

Fig. 4 is a fragmentary side elevational view of the luggage compartment with the cover opened and braced in such position by suitable means for easy access to the compartment;

Fig. 5 is a vertical transverse cross sectional view of a fragmentary portion of the luggage compartment substantially as viewed along the line 5—5 in Fig. 4;

3

Fig. 6 is an enlarged detail cross sectional view of a fragmentary portion of the luggage compartment illustrating one arrangement of securing the base of the compartment to a top of a conventional automobile;

Fig. 7 is a fragmentary side elevational view of the hinged portion of the carrier or compartment as viewed from the right hand side of Fig. 3 illustrating certain details of construction of the hinge employed for this turret top compartment;

Fig. 8 is a vertical transverse cross sectional view of a fragmentary portion of the compartment substantially as viewed along the line 8—8 in Fig. 7;

Fig. 9 is a side elevational view of a fragmentary portion of a car top using a base integrally formed with the top of the structure of the car, with certain portions broken away and in section to show the details of construction of this modification;

Fig. 10 is a front elevational view of same also broken away and in section to show the construction; and

Fig. 11 is a front elevational view of the integral turret top carrier with the cover removed and as utilized for transporting a boat.

Referring to Figs. 1, 2 and 3, the turret top luggage compartment in generally indicated at 1 as resting upon the top of a conventional automobile 2 and suitably attached thereto providing a carrier means for utility on special occasions or at all times to carry additional transportable objects which cannot be accommodated by the ordinary trunk baggage compartment of an automobile.

This compartment comprises a cover 3 having a hinged connection at 4, see Figs. 3, 7 and 8, with a base 5, the latter being secured to the auto top 6 by suitable fastening fixtures 7 which engage the rain beads or troughs 8 that are standard equipment on conventional automobile bodies.

The base 5 comprises a floor or deck 9 having a peripheral skirt 10 that is shaped with its upper edge having a peripheral offset and upstanding ridge 11 connecting the skirt 10 with the floor 9 to dispose the latter in a generally horizontal plane as determined by the shape of the body top engaging edge 12 of the skirt 10. The edge 12 of the skirt 10 is provided with a substantially continuous resilient footing means comprising a gasket 13 preferably constructed with a hollow contacting base portion 14, see Figs. 6 and 8, for engaging the top 6 of the car 2. Thus with the skirt of the base 5 formed to generally sit about the outer peripheral portion of the car top 6 particularly along the points of sharper curvature where the greatest strength of the top resides with respect to vertical supporting loads, this skirt 10 and its resilient gasket 13 forms a continuous seal for the base blending the structure of such base into the structure of the top thereby practically forming a continuation of the normal conventional automobile body structure to provide the supporting means for a turret top luggage compartment.

As seen in Figs. 2, 3 and 5, the base 9 is adapted to span the outer upwardly convex portion of the top without contacting the intermediate portion of the top so that the entire load carried upon the floor 9 will be supported about the peripheral portion of the top 6 as best illustrated in the drawings. To further reinforce the floor 9 of the base 5, this floor is provided with longitudinal downwardly formed ribs 15 supplemented by transversely formed ribs 16, with all of the ribs

4

intersecting and extending from front to back and side to side from adjacent the reinforced peripheral connection between the floor 9 and the skirt 10 as provided by the upstanding ridge 11 previously described.

The base 5 therefore is designed to provide a means to bridge the entire central area of the automobile top relieving the weaker or horizontal portions of such top from direct vertical supporting strains introduced by the carrier and luggage with the weight distribution being concentrated, as previously described, about those peripheral areas of the top having smaller radii establishing stronger supporting areas to better carry the load of the luggage compartment and its contents as well as the stresses induced through the fastening means 7 at their points of connection between the base 5 and the car top bead 8.

Since the floor 9 is of considerable area it is possible that the same, particularly under loaded conditions, might resort to diaphragming especially when the car is going over a road surface which may induce periodic up and down motion to the entire automobile. Since this might bring the floor 9 into contact with the top 6, it is proposed to use a sponge rubber pad or other cushioning means such as 17 illustrated in Fig. 5 which may be suitably attached at one or more points along the center of the floor 9 to provide a cushioning means for counteracting diaphragming or entirely eliminating the same as the case may be.

It should also be noted that the cover 3 and the base 5 are formed as complementary compartment units having a composite streamlined exterior which blends directly into the general streamlined shape of the car top and with the body of the automobile itself.

Referring to Figs. 4 and 5, it is seen that any suitable bracket means may be used for maintaining the top 3 in raised position with respect to the base 5 when loading or unloading the items or other objects from the luggage compartment. The bracket may be of a conventional type and is here shown as comprising a pair of links 18 and 19 pivotally connected with the cover 3 and base 5 with an appropriate latching means 20 interposed at the central pivoting point 21 to hold the bracket links vertically, thus maintaining the cover 3 in opened position. Conventional latch means 22 for engaging through a suitable opening in the floor 9 of the base may be utilized in connection with a key lock handle 23 also used for lifting the cover and lowering the same having the dual purpose of latching and unlatching the cover from the base.

As best illustrated in Figs. 6 and 8, it should be noted that the cover edge 24 is adapted to seat upon a ridge 25 disposed adjacent the reinforcing peripheral ridge 11 forming an overlapping seal which will prevent dust, dirt and water from entering the luggage compartment proper whenever the cover 3 is down in place and locked to the base 5 of the luggage compartment 1. It is obvious that resilient means may be employed either in connection with the edge 24 or the ridge 25 should that be desirable, although for normal use the construction illustrated in Figs. 6 and 8 should suffice.

In order to provide a means for disconnecting the cover 3 at the hinge 4 from the base 5 to bodily remove the cover, the hinge is made with a removable pin 26 as best illustrated in Figs. 7 and 8. This pin 26 passes through the loops of the cover hinge portion 27 and the base hinge por-

tion 28 and terminates with an upstanding end 29 having a small laterally bent portion 30 which passes through a suitable opening 31 formed in the cover 3 for the reception of a cotter pin 32 which is applied or removed from within the cover 3. An appropriately formed guard portion 33 may be employed as a part of the hinge portion 27 or as a separate bracket secured to the cover 3 to shield the end of the upstanding portion 29 of the pin 26 for the purpose of preventing the use of a hacksaw or chisel for severing the upstanding portion 29 of the pin 26. This guard 33 is relatively closed and has a tapered portion 34 suitably shaped as shown to permit limited pivotal movement of the pin 26 in order to remove the end 30 from the opening 31 in the cover 3 after the cotter pin 32 has been removed. Then the pin 26 may be pulled laterally from behind the guard 33 and out of the hinge loops of the hinge sections 27 and 28 separating the cover 3 from the base 5 to remove the former. The guard 33 permits endwise removal of the hinge pin 26. Other like arrangements may be substituted for this purpose. Simple means may be employed for detaching one end or the other of the bracket links 18, 19 to complete the separation of the cover from the base.

As best shown in Fig. 6, the fastening fixtures 7 are preferably constructed with threaded studs 35 having tough metal bands 36 secured thereto, these bands each terminating in the hook 37 for engaging beneath the connected portions of the rain beads 8 with the body top 6. Each of the fixtures 7 are adapted to fit through suitable openings formed in offsets 38 formed in the skirt 10 of the base 5 and nuts 39 are screwed upon the threaded ends of the studs 35 to increase the tension of the fastening fixtures and to tighten the base 5 against the top of the auto 6 through the instrumentality of the hook 37 about the underside of the bead 8 of the automobile body. The floor 9 of the base 10 is provided with suitable openings such as 40 appropriately positioned to permit access to the nut 39 in tightening or removing the fixtures 7 as the case may be.

In the foregoing construction the carrier for the turret top is designed for complete removal through use of the detachable fastening means described. Figs. 9 and 10 illustrate the use of a carrier that has its base formed integrally with the car top providing a turret top of special configuration comprising standard equipment for a car body of this type. The turret top 45 is deformed to provide a continuous peripheral ridge 46 having an inwardly sloping marginal section 47 supporting a substantially horizontally positioned deck 48. The elevation of the deck 48 is lower than the elevation of the normal crown 49 (in dot and dash lines) of the conventional car turret top thereby decreasing the overall height 60 of the car and carrier including the added cover 50.

The deck 48 may be ridged for re-enforcement but suitable cross bars 51 can be used to give strength to the deck, such bars being preferably welded to the deck and side portions 52 of the top 45 as seen in Fig. 10.

Cover 50 is constructed with an overhanging flanged peripheral edge 53 to lap the ridge 46 of the integral base structure to keep dust and dirt out of the carrier compartment proper. A suitable key lock hand latch 54 may be used to lock the cover 50 in place, such cover having a hinge arrangement 55 to attach same to turret top 45 for coaction with the deck structure to enclose

the baggage receiving area of the latter. Hinge means 55 may be of a removable type as described in connection with Figs. 1 to 8 to permit removal of the cover 50.

With cover 50 detached, the deck structure can be used for transporting other objects such as the boat 56 shown in Fig. 11. A plurality of headed studs 57 may be welded or otherwise secured to the upsweep portions 58 of the turret top 45 in positions below the parts of the deck structure covered by the flange 53 on cover 50 when the latter is being used as in Figs. 9 and 10. Studs 57 form anchoring means to receive the ends of a strap, cable, cord, chain, or any other suitable fastening means such as 59 for securing the object being transported.

The specific construction of turret top luggage compartments shown and described merely exemplify typical constructions embodying the inherent features involved in the present inventive concept. Changes and modifications are contemplated in the arrangement, form, and combination of parts, all within the purview of the present design, such modifications being governed by the breadth and scope of the claims appended hereto and directed to the new and novel luggage compartment design.

What I claim is:

1. A luggage carrier for an automobile top, said carrier comprising a base, said base having a floor, and a skirt connected with said floor, said skirt terminating in an edge having a contour substantially coincident with the general contour of the peripheral edge portions at the automobile top, means to secure said skirt with its edge in contact with said top to support said base in a substantially horizontal plane relative to said car by means of the shape of the terminal edge of said skirt, and resilient gasket means connected with said skirt edge to provide a footing having automatic adjustable contact with said automobile top to firmly support said base along the entire line of contact of the skirt with said top.

2. A luggage carrier for an automobile top, said carrier comprising a base, said base having a floor, a skirt connected with said floor and shaped to support said floor in spaced relation out of contact with the upper convex portion of the top, said skirt contacting the peripheral edge portions of said automobile top, said floor having ribs extending thereacross between oppositely located skirt portions and in predetermined locations out of contact with said top to provide a stiff floor to span said top, and means connected with said base for attachment with said automobile top to fix the location of the floor and floor ribs of said base with respect to said convex top.

3. A luggage carrier for an automobile top, said carrier comprising a base, said base having a floor, a skirt connected with said floor and shaped to support said floor in spaced relation out of contact with the upper convex portion of the top, said base and skirt connection including an upstanding offset wall to stiffen the periphery of said base at this point, said skirt contacting the peripheral edge portions of said automobile top, and said floor having ribs extending thereacross between oppositely located points on said upstanding offset wall and out of contact with said top to provide a stiffly suspended floor to span said convex top, and means connected between said base for attachment with said top to fix the location of the floor and floor ribs of said base with respect to said top.

4. An automobile turret top luggage carrier

comprising a base, a cover therefor, said base having a floor, a skirt connected with said floor and shaped to support same in spaced relation over the upper convex portion of the top, said base and skirt connection including an offset upstanding ridge to stiffen the periphery of said base at this point, said skirt being adapted to contact the peripheral edge portions of said turret top, said cover being arranged to coact with said base overlapping the offset ridge thereon to create a dust and water free closure, and said base having ribs extending thereacross between oppositely located portions of said upstanding ridge to provide a stiff floor to span said top, and means connected between said base and said turret top to fix the location of said base with respect to said top.

5. An automobile turret top luggage carrier comprising a base, a cover therefor, said base having a floor, a skirt connected with said floor and shaped to support same in spaced relation over the upper convex portion of the top, said base and skirt connection including an offset upstanding ridge to stiffen the periphery of said base at this point, said skirt being adapted to contact the peripheral edge portions of said turret top, said cover being arranged to coact with said base overlapping the offset ridge thereon to create a dust and water free closure, and said base having ribs extending thereacross between oppositely located portions of said upstanding ridge to provide a stiff floor to span said top, and means connected between said base and said turret top to fix the location of said base with respect to said top, and hinge means to permit said cover to swing open with respect to said base.

6. An automobile turret top luggage carrier comprising a base, a cover therefor, said base having a floor, a skirt connected with said floor and shaped to support same in spaced relation over the upper convex portion of the top, said base and skirt connection including an offset upstanding ridge to stiffen the periphery of said base at this point, said skirt being adapted to contact the peripheral edge portions of said turret top, said cover being arranged to coact with said base overlapping the offset ridge thereon to create a dust and water free closure, and said base having ribs extending thereacross between oppositely located portions of said upstanding ridge to provide a stiff floor to span said top, and means connected between said base and said turret top to fix the location of said base with respect to said top, and hinge means to permit said cover to swing open with respect to said base, said hinge means including removable mechanism to remove said cover from said base.

7. An automobile luggage carrier in combination with the automobile turret top comprising a substantially horizontally arranged deck, a skirt integrally formed with said deck and terminating in a raised border having peripheral connection with said deck, and structural members disposed across said deck to reinforce and stiffen the luggage carrying portion of said deck, said structural members providing a part of said deck and having connection with spaced points on peripheral portions of said raised border and adjacent said skirt.

8. An automobile luggage carrier in combination with the automobile turret top comprising a substantially horizontally disposed deck, a skirt integrally formed with said deck and terminating in a ridge having peripheral connection with said deck, said deck having portions thereof deformed and positioned to traverse said deck to reinforce and to stiffen the luggage carrying por-

tion of said deck, said deformed portions of said deck having connection with spaced peripheral portions of said skirt, and a cover for said deck to enclose a predetermined space above said deck, said cover having an edge adapted to seat upon said skirt ridge adjacent the spaced unions of said deformed deck portions and said skirt ridge and formed to overhang said ridge to keep out dust, dirt and water.

10. A base for a luggage carrier to engage the rounded peripheral edge portions of an automobile turret top, said base comprising a skirt having an edge for contacting said turret top edge portions, said base terminating upwardly in a peripheral offset wall to stiffen said upper terminal edge of said skirt, a luggage supporting floor connected with said offset wall to span the turret top in spaced relation thereto, said floor having depressed channels formed therein and extending across said floor below the luggage carrying plane thereof with the end portions of said channels connecting at spaced points on said offset wall and at opposite sides of said floor, and said channels being arranged to intersect at predetermined locations beneath said luggage carrying floor to contribute strength to suspending said floor in spaced relation with respect to the turret top and to counteract diaphragm action of the floor.

15. 10. A luggage compartment in combination with the turret top of an automobile comprising an upwardly formed skirt connected with peripheral edge portions of said turret top, a floor spanning the area within said skirt and adapted to support luggage, said floor forming the upper turret top enclosure for said automobile, said floor and skirt being annularly joined by an angularly disposed wall connected with said skirt and with said floor, said skirt and wall joint

20. forming a continuous ledge about said turret top, and a cover for said luggage carrying floor, said cover having its edge formed to rest upon the aforesaid ledge and having another portion of the edge depending and terminating below the plane of the ledge and outwardly with respect thereto.

25. 11. A luggage carrier in combination with the turret top of an automobile comprising an upwardly formed skirt as a continuation of the turret top and encircling the latter, a floor spanning the area within said skirt and adapted to support luggage, said floor providing the top enclosure for the automobile, and a joining wall connecting said floor with said skirt to complete the top enclosure, said joining wall being angularly disposed with respect to said floor and to said skirt to provide a strong ledge about the car top adapted for supporting and carrying articles upon said ledge that exceed the length or breadth of said luggage supporting floor.
